UNITED STATES PATENT OFFICE.

VICTOR MATALAVAGE, OF COLUMBUS, OHIO.

COMBINED DRILL AND VALVE GRINDER.

Application filed June 23, 1920. Serial No. 391,216.

To all whom it may concern:

Be it known that VICTOR MATALAVAGE, a citizen of the United States, residing at Columbus, in the county of Franklin and State 5 of Ohio, has invented certain new and useful Improvements in a Combined Drill and Valve Grinder, of which the following is a specification.

This invention relates to improvements in 10 an improved combination tool designed for garage and small machine shop work wherein is co-operatively provided a two multiple speed drill having self feeding features employed in conjunction therewith, and means 15 whereby the drill may be quickly and readily converted into a tool capable of being employed for the purpose of grinding the valves of an internal combustion engine.

Certain of the objects of the invention 20 are to provide a drill wherein is embodied a hollow frame capable of receiving a rotatable spindle, said frame being provided with a plurality of gears which are arranged concentrically with respect to said spindle, 25 and which gears are rotated by a main or master gear and are so arranged as to be coupled for rotation with said spindle by means of a plurality of selectively operable key elements, which are slidably carried in 30 conjunction with said spindle and are arranged to be inserted as desired in key ways provided in the gears, whereby upon the selective operation of said keys varying speeds of rotation will be imparted to said spindle 35 from the master gear, and similarly, said keys may be actuated so that the master gear will impart an oscillatory back and forth motion to the spindle, in order to adapt the latter to valve grinding movements; 40 in co-operative means for lowering said spindle within said frame during the carrying out of drill operations, said latter means consisting of a pivotally mounted lever, which has its lower end linked to an 45 eccentric pin carried by the master gear, so that upon the rotation of said gear said lever will be oscillated, the upper end of said lever being provided with a pivoted detent which engages with a ratchet member 50 threadedly connected with said spindle, whereby upon the oscillation of the lever said ratchet member may be rotated for carrying varying distances so that the down-feed of the spindle may be automatically effected during the operation of the master 55 gear; in the provision of an improved ad-

justable frame for effecting the support of the spindle as a whole and finally in the provision of a detachable balance wheel, which is adapted to be connected for rotation with 60 the master gear when the tool is employed as a drill, and disconnected from said tool when the latter is in use for valve grinding purposes.

With these and other objects in view, as 65 will appear as the description proceeds, the invention accordingly consists in the novel features of construction, combinations of elements and arrangements of parts, herein-after to be fully described and pointed out 70 in the appended claims.

In the accompanying drawing, forming a 75 part of this specification and in which similar characters of reference denote like and corresponding parts:

Figure 1 is a side elevation of the improved combination tool comprising the present invention,

Figure 2 is an enlarged elevation of the tool, parts being broken away and shown in 80 section for the purpose of disclosing underlying structure, and

Figure 3 is a transverse horizontal sectional view taken along the planes disclosed by the lines 3—3 of Figures 1 and 2. 85

Referring more particularly to the drawing, the numeral 1 designates the improved combination tool comprising the present invention in its entirety. In its preferred form, this tool consists of a main frame 2, 90 which includes a vertically extending portion 3, a laterally turned upper end 4, and a bifurcated laterally bent lower end 5. The slot 6 produced in the lower end is adapted to receive a ledge 7 of any suitable permanent character upon which the tool as a 95 whole may be detachably mounted. The connection between the end 5 and the ledge 7 may be effected through the provision of a vertical wing screw 8, which carries a flat 100 upper end 9 arranged to press against the under side of the ledge 7, whereby upon the tightening of the screw 8 the frame 2 is capable of being firmly held and supported in combination with the ledge, as it will be 105 clearly understood. Also, the vertical portion 3 of the frame is adapted to receive an adjustable table 10, which is vertically movable to and from the chuck 11 of the tool. The positions of the table 10 may be more 110 or less permanently maintained through the medium of the thumb screw 12, which lat-

ter is adapted to frictionally engage with the vertical portion of said frame 10.

Mounted upon the upper portion 4 of the main frame 2 is a supplemental or secondary frame 13, this frame having its lower portion 15 provided with a sleeve 14, which is adapted to be inserted in a vertical opening 16 provided in the end 4, and a thumb screw 17 is provided which is threaded into the side of the end 4 so as to impinge upon the sleeve 14, and to thereby securely connect the secondary frame with the main frame. The secondary frame, in turn, is provided with a removable side plate 18, which is secured to the upper and lower ends 19 of the secondary frame by the use of screws or the like. This plate 18 is provided with inwardly projecting arms 20 and 21, which are provided with vertically registering bores 22 for the reception of the vertically extending spindle 23 of the tool. The lower end of the spindle passes through the sleeve 14 and is suitably connected with the revolving chuck or tool holder 11. The upper end 25 of the spindle is provided with a threaded cap 24, in which is received the lower spherical end 25 of a feed screw 26, the latter being, in turn, threaded into an adjusting nut 27, which is positioned between the upper end 30 of the secondary frame and an integral finger 28 formed therewith. By this construction the nut 27 will be maintained against vertical movement, and yet will be permitted to rotate so as to effect the raising 35 and lowering of the screw 26 and consequently the spindle 23. If desired, the upper end of the screw may be provided with a key way 29 in which a key 30, carried by the upper end of the secondary frame, may be positioned so that the screw will be prevented from rotating, that is, the operation 40 of the nut 27 will effect vertical movement on the part of the screw without rotating the latter, and hence through the provision 45 of the cap 24 and the spherical end 25 of the screw a good bearing is provided to permit of the more or less rapid rotation of the spindle.

In order to effect the rotation of the spindle the side of the secondary frame is provided with a bearing in which is received the operating shaft 31. As shown in Figure 1, this shaft is provided with a squared end, which is adapted to receive any suitable form of manipulating device, not shown, such for example as a hand crank or a power wheel. The inner end of the shaft 31 is connected in any suitable manner with a master or compound gear 32, which is of peculiar configuration and consists of an outer series of gear teeth 33, an inner gear 34, and intermediate series of segmental gear teeth 35 and 36. These teeth, as will be obvious, may be formed integrally or separately with respect to the gear 32 as a

whole, in order that they will rotate in unison. Also, the outer edge of the gear 32 is provided with gear teeth 37, the function of which will be hereinafter more fully described.

The teeth 33 are employed to drive the spindle 23 at its highest or first speed, and to this end the said gear teeth 33 mesh with a bevel pinion 38, which loosely surrounds the spindle 23 and is confined for rotation 75 between the lower arm 21 and the lower portion of the secondary frame. To connect the pinion 38 for rotation with the spindle, the latter is provided with a vertically extending groove 39, in which is fit a sliding bar 40 having a key extension 41 integrally formed upon its lower end. This bar is centrally provided with a recessed extension 42, in which is positioned a ring 43, the latter being disposed within the hub of the arm 20. The 80 arm 20, in turn, is provided with a slot 44 having offset portions 45, and this slot and its offset portions are adapted to receive an actuating pin 46 connected with the ring 43. Normally, the pin 46 rests within the offset 85 portion 45 formed midway in the slot 44, but it will be observed by turning the pin laterally the same may be moved out of the intermediate offset portion 45 and elevated so that the pin may be positioned within 90 the offset portion formed in the upper end of the slot. This movement on the part of the pin results in raising the ring 43 so that corresponding elevation of the bar 40 is effected, and this movement of the bar permits the key extension 41 thereof to enter 95 into one or the other of the key way slots 47 provided in the pinion 38. Therefore, the rotation of the master gear will result in the rotation of the pinion 38, and when the 100 key extension 41 is within the slot 47, the rotation of the pinion will result in turning the spindle 23 at its highest rate of speed. To rotate the spindle at a lower rate of speed, the pin of the ring 43 is moved so 105 that it occupies its lower most position within the slot 44, thereby causing the extension 42 to engage within one of the key ways formed in the pinion 38, which pinion being in mesh with the gear 34 will rotate 110 the spindle 23 at its slowest rate of speed. It will be observed that the pinion 38 is loosely mounted for rotation around said spindle and between the arms 20 and 21 of the supplemental frame. The key extensions 115 41 and 42 are so arranged that the same may be both out of engagement with their respective pinions at the same time and to be also capable of occupying but one pinion during a given operation. Through this 120 construction a multiple speed drill is provided which may be simply, positively and easily controlled.

When it is desired to employ the tool as a valve grinder, the pin 46 is moved so that 130

- the same will occupy the lower offset portion 45 of the slot 44, thus disconnecting the pinions 38 and 48 from connection with the spindle. Then, the opposite side of the 5 spindle is provided with an elongated slot 49, in which is positioned a vertically adjustable bar 50. This bar carries key extensions 51 and 52, the former of which being movable into and out of any one of a 10 plurality of key ways provided in a bevel pinion 53, which is located between the arms 19 and 20 of the supplemental frame and loosely surrounds the spindle 23. The lower extension 52 is similarly movable into any 15 one of a plurality of key ways provided in a bevel pinion 54, which is situated immediately above the pinion 38. The pinion 53 is so disposed as to engage with the gear teeth 35, while the pinion 54 is situated to 20 similarly engage the gear teeth 36. To couple these pinions 53 and 54 with the spindle, the bar 50 is notched to receive a ring 55, from which a pin 56 projects, the latter being received within a slot 57 provided in the arm 20. The upper end of this 25 slot 57 is provided with an offset extension 58 which normally receives the pin 56, and thereby maintains the bar 50 elevated so that its key extensions 51 and 52 will be out of 30 engagement with their respective pinions 53 and 54. However, by rotating the ring the pin 56 may be permitted to move vertically in the slot 57 so that the bar 50 as a whole will be lowered, thus causing the extensions 35 51 and 52 to enter the key ways in the pinions 53 and 54, thus directly connecting the latter simultaneously for rotation with the spindle. The arrangement of the teeth 35 and 36 is such that the gear 36 will 40 rotate the pinion 54 in a given direction upon the rotation of the master gear, and consequently the spindle 23, and when said teeth 36 are disengaged from the gear 54, the teeth 35 will then mesh with the pinion 45 53, thereby causing the latter to rotate in the opposite direction as compared with the direction of rotation of the pinion 54. This arrangement imparts to the spindle 23 an oscillatory back and forth motion, which 50 is highly essential in valve grinding operations. Since the teeth 36 are greater in number than the teeth 35, it will be manifest then that successive operations of said pinions 53 and 54 will impart progressive rotation to the spindle 23 in a given direction, a feature which prevents the valve grinding tool from starting and stopping when operated by the spindle 23 at given or fixed 55 positions.
- 60 When the tool is employed as a drill, a balance wheel 59 is provided for rendering the operation of the drill as a whole smooth and uniform, and when said tool is employed as a valve grinder the balance 65 wheel is detached from the tool so as to prevent the same from interfering with the alternate revolving movements of the spindle. To this end, the supplemental frame receives a removable shaft 60, which carries a spur gear 61 so disposed as to normally mesh with the teeth 37, whereby when the master gear is revolved motion will be imparted to the shaft 60, the latter in turn carrying at its outer end the balance wheel 59. To mount the shaft 60 in position, use 70 is made of a bracket 62, which is designed for connection with the plate 17. This bracket is provided with a pair of dowel pins 63, which are received within openings provided in the plate 17 and also, said bracket is provided with a central opening arranged to register with a corresponding opening provided in said plate. A headed bolt 64 is passed through these openings and has its inner threaded end arranged to receive a wing nut 65, whereby upon the tightening of the latter the said bracket will be drawn into tightly clamped engagement with the plate 17 so as to provide 75 a secure yet detachable journal for the shaft 60. The end of the shaft away from the bracket 62 is adapted to be removably inserted within an opening provided in the supplemental frame, the latter opening serving as a journal for the inner end of said 80 shaft, and hence does not interfere with the application or removal of the balance wheel structure in connection with the supplemental frame as a whole.
- To provide for the automatic downward 85 feed of the spindle 23 when the tool is employed as a drill, the master gear 32 is provided with an eccentrically disposed wrist pin 66, to which is connected a short link section 67. The outer end of this link is 90 pivotally connected as at 68 with the lower end of an actuating lever 69. This lever is provided centrally with an elongated slot 70, in which is positioned a bolt 71, the latter having its headed end mounted within a 95 similar slot 72 provided in an extension 73 integrally formed with the supplemental frame. Serrated collars 74 are positioned between the inner face of the extension 73 and the lever 69 so as to hold the latter in 100 its proper position of actuation. Also, the threaded end of the bolt 71 is adapted to receive a wing nut 75 which is employed to maintain the various fulcrum positions 105 of said lever with respect to the bolt 71. By 110 vertically adjusting said bolt it is manifest that the upper end thereof may oscillate varying distances, a feature which affords considerable adjustment in the downward feed of the spindle 23. The inner face of 115 the extension 73 is notched as at 76 to receive the correspondingly notched face of the outer collar 74, and similarly, the inner collar 74 is also provided with a notched 120 face 77 which engages with the side of the 125

lever 69, the meeting faces of said collars being perfectly plain so that the lever may oscillate without undue friction or loss of adjustment.

5 The upper end of the lever 69 is provided with a pivoted detent or pawl 78, which is adapted to engage with a plurality of ratchet teeth 79 provided upon the adjusting nut 27. This pawl may be spring 10 pressed into engagement with the teeth 79 or may be permitted to fall into the latter by virtue of gravity, as desired. It will therefore be manifest that when the tool is employed as a drill the rotation of the master gear will result in the oscillation of the lever 69 and by virtue of the pawl construction 78 connected with the upper end thereof, motion will be imparted to the nut 27 so as to effect a graduated lowering of 15 the spindle 23 during the operation of the device. The speed of descent of the spindle may be governed by adjusting the position of the bolt 71 which controls the extent of oscillation or the throw of the upper end 20 of said lever and its pawl 78. The key ways provided in the drill spindle for the reception of the bars 40 and 50 are of sufficient length to permit said drill to assume 25 its lowermost position without interfering with the operation of the bars or affecting 30 their adjustments in coupling or uncoupling their respective pinions to the spindle 23.

It will of course be understood that the 35 chuck may be removed from engagement with the spindle when the tool is not employed for drilling purposes and that an ordinary valve engaging tool, not shown, may be connected with said spindle for the purpose of effecting the grinding of valve 40 seats. Also, it will be observed that the secondary frame is removable from engagement with the main frame, and hence when 45 valve grinding operations are to be carried out the secondary frame is removed from its position within the main frame, in order that the tool will possess the advantage of 50 portability and to enable the same to be readily handled in valve grinding manipulations.

55 In view of the foregoing description taken in conjunction with the accompanying drawing, it will be apparent that a combination tool is provided of very considerable utility and one which may be quickly 60 changed to adapt the same to the peculiar class of work at hand. The parts are slide- 65 able and positive in operation and by virtue of their substantial construction are not likely to become out of order or to occasion considerable repair. The upper portion of 70 the supplemental frame may be provided with a hand knob 80, and the lower end of the sleeve 14 is provided with a hooked ring 81, which may be employed for the purpose 75 of enabling work to be chained in connec-

tion with the frame, in lieu of the table 10. The tool therefore comprises a combination drill and valve grinder, together with auxiliary features to effect the positive operation of each part of the tool, convenience in operation being also taken into consideration. In view of the foregoing it is believed that the operation, construction and principles of the invention will be readily understood by those versed in the art, and therefore a more extended explanation has been accordingly omitted.

What is claimed is:

1. In a combination tool of the character described, a frame, a compound gear rotatably carried by said frame, a tool operating spindle rotatably journaled within said frame, means co-operative with said spindle and said gear adjustable to cause selective rotation of said spindle in a predetermined direction and to effect an oscillatory back and forth motion thereof.

2. In a compound tool of the character described, a frame, a compound gear rotatably journaled in connection with said frame, said gear being provided with spaced sets of annularly and concentrically disposed gear teeth, a tool spindle, pinions in mesh with the sets of gear teeth provided upon said compound gear and normally disposed to loosely surround said spindle, a sliding key structure capable of selectively connecting said pinions with said spindle, whereby upon the rotation of said gear said spindle may be continuously rotated in a given direction at speeds determined by the pinion coupled to the spindle, and a plurality of segmental sets of gear teeth carried by said compound gear, pinions loosely carried by said spindle and capable of meshing with said segmental sets of gear teeth, and clutch mechanism for connecting said latter pinions with said spindle.

3. In a tool of the character described, a frame, a tool operating spindle rotatably journaled within said frame, means for rotating said spindle, comprising a main compound gear rotatably journaled in connection with the frame, concentrically disposed annular sets of gear teeth carried by said gear, pinions normally disposed to loosely surround said spindle and to mesh with said gear teeth, a key slidably mounted in a groove provided in said spindle, said key being provided with spaced key extensions, and an adjusting member connected with said key and operating in a slot provided in said frame for selectively moving said key extensions into engagement with said pinions, whereby the latter may be selectively coupled for rotation in connection with said spindle to permit the compound gear to rotate the spindle at multiple speeds.

4. In a tool of the character described, a frame, a spindle rotatably mounted in

- connection with said frame, a compound gear for effecting the rotation of said spindle, said gear being formed to include spaced sets of concentric annular gear teeth, 5 pinions normally in mesh with said gear teeth and disposed to loosely surround said spindle, a slidably mounted key member positioned in a groove provided in said spindle, extensions formed with said member 10 and ring surrounding said spindle and positioned within the recesses provided in said member, and an actuating device projecting from said ring and disposed in the slot provided in said frame, whereby through 15 the agency of said device said key member may have its positions controlled so that the extensions thereof may be selectively projected into engagement with key ways provided in said pinions, thereby permitting 20 said gear to rotate said spindle at varying or multiple speeds.
5. In a drill, a frame, a tool spindle rotatably journaled within said frame, means for transmitting the motion of said gear to 25 said spindle, a feed screw formed with the upper end of said spindle, a nut mounted within said frame and in threaded engagement with said screw, ratchet teeth formed upon said nut and lever connected with said 30 frame and having an intermediately located adjustable fulcrum, means operated from said gear to oscillate said lever, and a pawl pivotally connected with the upper end of said lever and in engagement with the teeth 35 of said nut to effect the turning of said nut and the longitudinal movement of said screw and spindle during the rotation of said gear.
6. In a tool of the character described, a frame, a tool spindle rotatably mounted 40 within said frame, a driving gear, means for transmitting the motion of said gear to said spindle, a feed screw having a swivel connection with the upper end of said spindle, and a nut rotatably journaled within 45 said frame and threaded into engagement with said screw, means for preventing the rotation of said screw during the rotation of said nut and yet serving to permit the screw to move vertically, and means operated by the rotation of said gear to automatically rotate said nut varying distances.
7. In a tool of the character described, a frame, a spindle rotatably mounted within 50 said frame, a gear for rotating said spindle, a feed screw carried by the upper end of said spindle, means for operating said screw comprising an oscillatory lever, said lever having an elongated slot formed therein intermediately of its ends, an adjustable fulcrum device positioned within said slot and 55 within a co-operative slot provided in said 60 frame and said device serving to regulate the throw of the effective end of said lever, a nut threaded in engagement with said screw, said nut having one of its faces provided with ratchet teeth, a pawl carried by the effective end of said lever and disposed to engage with said teeth, the engagement of said pawl with said teeth being regulated by 65 said adjustable fulcrum device, and a link connected with the other end of said lever and eccentrically with the axis of said gear, whereby upon the rotation of the latter said lever will be oscillated.
8. In a compound tool of the character 70 described, a frame, a spindle rotatably connected with said frame, a compound gear rotatably supported upon said ring, means co-operative with said gear to effect continuous rotation of said spindle in one direction or an oscillatory back and forth motion thereof, a balance wheel, a shaft for said balance wheel driven from said gear, and means for readily permitting of the removal of said balance wheel and shaft from 75 said frame when oscillatory motion is to be imparted to said spindle.
9. In a combination tool of the character 80 described, a main frame, a supplemental frame a spindle journaled in said supplemental frame, a master gear carried by said supplemental frame, the said supplemental frame and spindle being removable from the main frame as an operative unit, and means co-operative with said gear to impart a continuous rotary motion to said spindle or an 85 oscillatory back and forth motion thereto.
10. In a valve grinder, a frame, a tool 90 spindle rotatably mounted within said frame, an actuating gear rotatably journaled in connection with said frame, said gear being provided with segmental sets of gear teeth, pinions journaled in said frame and normally disposed to loosely surround said spindle, said pinions being arranged to engage 95 with said gear teeth and located on opposite sides of the axis of said actuating gear, means for connecting said pinions with said spindle, comprising a slidably mounted key member disposed within a groove provided 100 in said spindle, key extensions formed upon said member, a ring surrounding said spindle and disposed within a recess provided in said member, and an actuating device extending from said ring and disposed within 105 a slot formed in said frame, said device serving to permit of vertical adjustment on the part of said key member to simultaneously project the extensions thereof into or out of 110 key ways provided in said pinions.
- In testimony whereof I affix my signature.
- VICTOR MATALAVAGE.
